Term of patent 7 years

Int. Cl. D7—99

U.S. Cl. D49—35

FIG. 1 is a perspective view of a sand urn or similar article showing my new design;

FIG. 2 is a sectional view taken on line 2—2 of FIG. 1, and

FIG. 3 is a sectional view taken on line 3—3 of FIG. 1.

The characteristic feature of the design resides in the contrasting surface texture or appearance of the circumferential band between the spaced second and third annular beads from the bottom.

I claim:

The ornamental design for a sand urn or similar article, as shown and described.
